UNITED STATES PATENT OFFICE.

ROBERT SCHEUFFGEN, OF SALZKOTEN, GERMANY, ASSIGNOR TO FABRIK EXPLOSIONSSICHERER GEFÄSSE, G. M. B. H., OF SALZKOTEN, WESTPHALIA, GERMANY, A CORPORATION OF GERMANY.

METHOD OF EXTINGUISHING FIRES.

1,118,952.

Specification of Letters Patent.

Patented Dec. 1, 1914.

No Drawing.

Application filed March 21, 1912. Serial No. 685,215.

To all whom it may concern:

Be it known that I, ROBERT SCHEUFFGEN, a citizen of the Empire of Germany, and residing at Salzkotten, Westphalia, Germany, 5 have invented a certain new and useful Improved Method of Extinguishing Fires, of which the following is a specification.

My invention relates to methods of extinguishing fires.

10 It is well-known to extinguish fires by producing a layer of foam which spreads out over the seat of the fire and, as it were, smothers the fire by shutting off the air from it. Heretofore the foam was produced by 15 employing two liquids, generally kept separate from one another, which when mixed together acted on one another and generated a gas, *e. g.* carbonic acid gas, and to one of which was added a foam-forming substance, 20 *e. g.* extract of licorice root. These liquids, generally kept separate from one another, were either contained in suitably constructed manual fire-extinguishers which, when in use, operated in the manner of gas-syringes, or were kept ready in special vessels 25 so that they could be brought together inside or outside the burning objects and form foam.

The method according to my invention 30 differs from this well-known method in that for producing foam I do not employ liquids which are generally kept separate from one another, but solid chemicals in the form of pieces or powder which contain foam-forming substances or to which such substances 35 are added. These solid chemicals may be kept either inside the chambers, tanks or the like to be protected, or in readiness outside the same. When required to be used, these 40 chemicals are dissolved by adding a solvent, *e. g.* water, whereby the foam is produced. If the solid chemicals are outside the tanks, chambers or the like to be protected, the 45 foam formed by adding the solvent, *e. g.* water, can be supplied under the pressure produced by the formation of the foam through piping to the seat of the fire or to the endangered places. In order efficiently to utilize this pressure produced when the foam 50 is being formed I preferably store the solid chemicals in closed boilers. When the solid chemicals are placed into the receptacles themselves which are to be protected, *e. g.* in tanks for holding readily combustible

liquids, owing to the light specific weight of 55 the foam formed by supplying water or other suitable solvent it will rise to the surface of the burning material, *e. g.* a readily combustible liquid, spread out at the surface of the same and smother the fire by shutting 60 the air off from it.

As suitable chemicals I may employ, among others, the substances classed as effervescent powders to which foam-forming substances, such as extract of licorice root, 65 Panama wood or the like are added. Accordingly, the following may be used, for example:—aluminium sulfate and bicarbonate of soda, oxalic acid and bicarbonate of soda, sodium sulfite or bisulfite and aluminium sulfate.

I claim:—

1. The herein described method of extinguishing fires in tanks containing inflammable liquids lighter than water, said 75 method consisting in sinking to the bottom of the tank, previous to the possible fire, two separate solid chemicals containing foam forming substances; keeping said chemicals in place until the time of need; 80 and spraying water into said tank, at the time of need, whereby the water sinks to the bottom, dissolves the chemicals, permits them to unite, give off non-combustible and non-combustion-supporting gas, and form 85 foam which floats to the surface of the liquid spreads itself thereover, holds the air from contact therewith and then prevents the liquid from burning.

2. The herein described method of extinguishing fires in tanks containing inflammable liquids lighter than water, said method consisting in placing in communication with the liquid, previous to the time of need, a mixture of dry chemicals, containing a foam forming substance and adapted to give off non-combustible and non-combustion-supporting gas when dissolved in water, the chemicals being so placed that the foam produced thereby can rise to the 90 surface of the liquid; and, at the time of need, introducing water into the tank, the water sinking in the tank and dissolving the chemicals producing foam which floats upon the surface of the liquid and protects the 100 liquid.

3. The herein described method of extinguishing fires in tanks containing in-

flammable liquids lighter than water, said method consisting in sinking in the tank two solid chemicals containing a foam forming substance; and sinking water in said tank whereby the chemicals are dissolved, chemical action takes place, non-combustible and non-combustion-supporting gas is given off, foam is formed, floats upon and covers the surface of the liquid and holds the air from contact therewith and prevents combustion.

4. Process for the extinguishing of fire in tanks containing easily inflammable liquids, consisting of the fact that in advance a dry mixture of chemicals that develop non-combustible and non-combustion-supporting gas containing foam upon being dissolved by water are arranged at a place near the bottom of the tank to be protected, this place being so selected that the foam produced within the inflammable liquid can rise to the surface thereof, and that at the given moment water can be introduced into the inflammable liquid, which water sinks in the tank and dissolves the chemicals placed near the bottom, producing foam.

5. A process consisting in sinking into a vessel of inflammable liquid lighter than water two separate solid chemicals insoluble

in said liquid and adapted to give off non-combustible and non-combustion-supporting gas when dissolved; retaining said chemicals in solid state in said vessel, until time of need; and then dissolving said chemicals by sinking water in said tank.

6. A process consisting in retaining in a vessel of inflammable liquid lighter than water, until the time of need, two separate solid chemicals insoluble in said liquid and adapted to give off non-combustible and non-combustion-supporting gas when dissolved; and in the time of need dissolving said chemicals with water.

7. A process consisting in retaining, until the time of need, in a single vessel of inflammable liquid free from water, two separate solid chemicals insoluble in said liquid and soluble in water and adapted to give off non-combustible and non-combustion-supporting gas when dissolved, and in the time of need sinking water in said vessel.

In testimony whereof, I affix my signature in the presence of two witnesses.

ROBERT SCHEUFFGEN.
